ELECTRIC WRITING INSTRUMENT

Herman Rapaport, Chicago, Ill.

Application January 28, 1946, Serial No. 643,918

4 Claims. (Cl. 219—29)

1

The present invention relates to improvements in electric writing instruments and more particularly to instruments of the type used for making inscriptions on leather, wood or other materials which are susceptible of being marked or branded by the imprint of a hot point thereon.

An object of the invention is to provide an instrument of the character described with means for preventing overheating of the holder or body portion so that the instrument may be used without discomfort to the person using the same.

Another object is to provide a burning tool with a heat radiating element embodying means to insure maximum dissipation of heat.

Another object of the invention is to provide a holder for an electric writing instrument in which electrical terminal contacts, provided therein, are adequately protected so as to prevent inadvertent contact therewith and possible injury to the person using the instrument.

Another object is to provide an electric writing instrument with a detachable heat-radiating element, including a writing tool, which is easily mounted within the holder and suitably connected with a source of electric current.

Another object of the invention is to provide a relatively simple and inexpensive electric writing instrument which is designed to approximate the form of an ordinary writing instrument such as, for example, an ink pen or pencil, and which may be used with equal facility for writing.

Other and further objects of the present invention will be apparent from the following description and claims and are illustrated in the accompanying drawing which, by way of illustration, shows a preferred embodiment and the principle thereof which is considered to be the best mode contemplated for applying that principle. Other embodiments of the invention, embodying the same or equivalent principle, may be used and structural changes may be made as desired by those skilled in the art without departing from the present invention or the purview of the appended claims.

In the drawing:

Fig. 1 shows an elevational view of the improved electric writing instrument.

Fig. 2 is an enlarged longitudinal sectional view through a fragment of the writing instru-

2

ment illustrating the holder and heat-radiating element separated.

Fig. 3 is a transverse sectional detail view taken on line 3—3 of Fig. 2.

5 Fig. 4 is a transverse sectional detail view taken on line 4—4 of Fig. 2.

The electric writing instrument illustrated in the accompanying drawing includes, in general, a holder 11 and a removable heat-radiating element 12 having a writing implement or tool 13 extending therefrom. In use, the writing implement or tool 13 is adapted to be heated, by means of electric current supplied to a resistance unit embodied therein, sufficiently to burn inscriptions or any imprint desired upon leather, wood or other materials susceptible of so being marked.

The holder 11 preferably is fashioned from heat-resisting material substantially in the form of a tapered cylinder and is provided on its inside circumferential face with circumferentially spaced longitudinal ribs 14 which terminate short of one end thereof. The inside face of the holder 11, beyond the ends of the ribs 14, is flared slightly outwardly, as at 15, towards the end thereof so as to provide in effect a receptacle 16 into which the heat-radiating element 12 is adapted to be inserted. A pair of electrical conductors 17 are extended into the holder 11, as at 18, and these conductors are connected one to each of a pair of terminal contacts 19 projecting out of the end of an outlet socket 20 arranged within the holder adjacent to the ends of the internal ribs 14.

As best shown in Fig. 2, the terminal contacts 19 extend into the outlet socket 20 and terminate one within each of a pair of spaced slotted openings 21 provided in said socket. A suitable cement or other non-conductor of electricity is applied, as at 22, over the innermost end of the outlet socket 20 to retain the terminal contacts 19 in place therein. The outlet socket 20 is, of course, fashioned from material having high electrical resistance, such as ceramic, and it is provided on the end into which the openings 21 communicate with an external flange 23 of sufficient diameter to slightly overlie the ends of the internal ribs 14 to thereby limit insertion of the outlet socket 20 therein. A suitable adhesive or cement may be applied, as at 24, to the circumferential surface of the outlet socket 20 so

as to adhesively bind the outlet socket to the ribs and thereby prevent its displacement.

It should be evident, at this time, that the terminal contacts 19 are positioned well below the outwardly disposed end of the outlet socket 20, which in turn is located inwardly of the end of the holder 11. This construction affords means whereby inadvertent contact with the terminal contacts 19 is prevented. The holder 11, and particularly the receptacle 16 provided in the end thereof, is adapted to telescopically receive the heat-radiating element 12.

Referring particularly to the detailed disclosure of the heat-radiating element in Fig. 2, said element consists of a substantially cylindrical body 25 fashioned from ceramic or other material having relatively high electrical and heat-resisting qualities. The body 25 is provided with a plurality of axially aligned bores 26, 27 and 28 providing internal shoulders 29 and 31 at the respective junctures thereof, and the outside surface of said body is fashioned with a plurality of circumferentially spaced longitudinally extending radial fins 32 which serve to increase the heat radiation.

A tubular writing tool or implement 33, closed and pointed at one end, as at 34, is fitted within the bore 26 and extends beyond one end of the body. The inner end of said tool 33 is provided with radial external lips 35 adapted to rest against the shoulder 29 to prevent withdrawal of the tool from the body 25. A heat-resistance unit 36 of any conventional construction is inserted into the tubular writing tool 33 and said heat-resistance unit is connected, as by means of wires 37 and 38, to terminal blades 39 which project outwardly from the other end of the body 25. As shown, the terminal blades 39 are each provided with an offset portion 41 adapted to rest against the shoulder 31 to limit inward movement thereof during assembly, and a plug 42 preferably fashioned from hard rubber, Bakelite, or other material having relatively high electrical resistance, is fitted over said terminal blades to retain them in their spaced apart relationship. The plug 42 has an external diameter corresponding substantially to the internal diameter of the bore 28 so as to fit snugly therein and provide a firm mounting for the terminal blades 39.

A cement 43 having high electrical resistance qualities is spread over the plug 42 to firmly bind said plug within the body 25 and to prevent inadvertent removal and subsequent displacement of the terminal blades. The interior of the body 25 defined by the intermediate bore 27 preferably is suitably filled with mica or other material having high electrical resistance qualities.

In use, the heat-radiating element 12 is telescoped into the holder receptacle 16 and when in this position the terminal blades 39 extend through the slotted openings 21 in the outlet socket 20 so as to make an electrical circuit between the heat-resisting unit 36 and the source of electrical current which is supplied through the conductors 17. The writing instrument is prevented from over-heating to an objectionable degree by the presence of the internal ribs 14 and the external fins 32, it being evident that the internal ribs 14 provide ample space, as at 44 (Fig. 3), between the inside surface of the body 11 and the outlet socket 20 to allow for the free circulation of air through the holder 11. The fins 32 on the heat-radiating element 12 also provide passage-ways leading from the atmosphere into communication with the spaces 44 and further, said fins provide spaced surfaces which afford means whereby the instrument may be firmly grasped without discomfort to the user.

It should be quite evident, at this time, that various types of writing implements or tools 33 may be provided in heat-radiating elements of the kind shown, and that various heat-radiating elements may be mounted within the holder 11 easily and quickly so as to adapt the instrument to a multitude of specific uses.

Although an exemplary form of the improved electric writing instrument has been disclosed in the accompanying drawing and described in detail hereinabove, it should be understood that the invention is capable of embodying a wide variety of modifications in detail construction without departing from the spirit of the invention or the scope of the appended claims.

I claim:

1. An electrical writing instrument comprising a tubular holder, longitudinal ribs on the inside face of said holder substantially coextensive with the length thereof but terminating short of one of its ends, an electrical outlet socket having electrical connections with a current source mounted firmly in said holder, said socket being of a size to fit snugly within the annular space defined by the inner faces of said ribs so as to provide segmental air spaces between the socket and the inside face of said holder, and a heat-radiating element including a burning tool inserted into the holder over said socket, said heat-radiating element having longitudinal heat-radiating fins on its outside surface effective to maintain air spaces connecting the handle interior with atmosphere, and a pair of terminal blades on said element engageable in said outlet socket to connect the burning tool with the current source.

2. A writing instrument of a kind to be heated electrically comprising a holder in the form of a cylindrical body, an electrical outlet socket mounted within said body adjacent one end, longitudinal internal ribs in said body to hold the electrical outlet socket spaced from the inside face of the cylindrical body so that air may circulate freely within the holder, means connecting said socket with a current source, a heat-radiating element including a writing tool having an electrical-resistance unit therein mounted in said holder end, said element having heat-radiating fins providing air passageways between adjacent fins leading from the interior of the holder to the atmosphere, and terminal blades on said element electrically connected with the electrical-resistance unit engageable in said outlet socket so as to complete an electric circuit between the unit and a source of electric current.

3. An electrical writing instrument comprising a tubular holder, an electrical outlet socket having electrical connections with a current source and mounted firmly in said holder, means for locating said socket substantially axially of said holder, but providing air spaces between said socket and the inside surface of said holder, and a heat-radiating element, including a burning tool receivable in said holder, said heat-radiating element having longitudinal heat-radiating fins on its outside surface effective to maintain air spaces connecting the holder interior with the atmosphere, and a pair of terminal blades on said element engageable in said outlet socket to connect the burning tool with the current source.

4. An electrical writing instrument comprising a hollow cylindrical body, an electrical socket

mounted within said body adjacent one end thereof, means for locating said socket substantially axially of said body but providing air spaces between said socket and the inside surface of said body so that air may circulate freely within the body, means connecting said socket with a current source, a heat-radiating element including a writing tool having a heat-resistance unit therein mounted in said body end, said element having heat-radiating fins providing air passage- 10 ways between adjacent fins leading from the interior of the body to the atmosphere, and terminal blades on said element electrically connected with the resistance unit and engageable in said outlet socket so as to complete an electric 15 circuit between the unit and the source of electric current.
